Primary Examiner — Cynthia Ramirez(74) *Attorney, Agent, or Firm* — Loginov & Associates, PLLC; William A. Loginov(57) **CLAIM**

The ornamental design for a conveyor idler, substantially as shown.

DESCRIPTION

FIG. 1 is a perspective view of a conveyor idler showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures show portion of the conveyor idler, which form no part of the claimed design.
